UNITED STATES PATENT OFFICE.

MAXIMILIAN WALZ, OF PITTSBURG, PENNSYLVANIA.

FORMER FOR HOLLOW POTTERY-WARE.

SPECIFICATION forming part of Letters Patent No. 246,576, dated August 30, 1881.

Application filed May 5, 1881. (No model.)

To all whom it may concern:

Be it known that I, MAXIMILIAN WALZ, of Pittsburgh, in the county of Allegheny and State of Pennsylvania, have invented a new and useful Improvement in Formers for Hollow Pottery-Ware; and I do hereby declare the following to be a full, clear, and exact description thereof, reference being had to the accompanying drawings, forming part of this specification, in which—

Figure 1 is a plan view of my improved former. Fig. 2 is a plan view of the same, showing the former extended. Fig. 3 is a plan view of the rear face of the same. Fig. 4 is a detached plan view of the upper side of the larger movable plate or rib. Fig. 5 is a detached plan view of the upper side of the stock. Fig. 6 is a detached plan view of the connecting plate or rib. Fig. 7 is a detached plan view of the under side 20 of the larger movable plate or rib. Fig. 8 is a detached plan view of the under side of the stock. Figs. 9 and 10 are detached plan views of the under sides of the shoes, which fit on the ribs e^1 and h^2 .

Like letters of reference indicate like parts wherever they occur.

My invention relates to an improvement in formers used in the manufacture of pottery-ware; and it consists, mainly, in the combination, with a fixed or stationary stock, of a former-plate adapted to slide thereon, the parts being connected by pins and cam-slots, so that the former-plate may be progressively projected beyond the stock; and, secondarily, in specific combinations, hereinafter more fully set forth.

Heretofore it has been customary in the manufacture of earthenware vessels to place the clay in the mold on the wheel, and form the inside surface of the vessel by means of a plain mandrel or former, or, where the inside surface is other than a plain one, the work has to be accomplished by means of the hand of the workman. Consequently the operation is slow and tedious, and a skilled workman can manufacture only about sixty vessels—such as tea-pots—per day. Besides this, the vessels vary in weight and size. By the use of my improved former, however, the operation of manufacturing vessels of earthenware is simple and rapid, the workman being able to manufacture, on an average, six hundred vessels per day instead

of sixty, and the vessels so formed are of an equal size. My former may be shaped so as to manufacture many kinds of earthenware vessels, the form shown in the drawings, however, and described in this specification is specially adapted for the manufacture of tea-pots.

The principal parts of my improved former are, a stationary stock or plate of metal, over which is a movable plate or rib, which is connected with the stationary stock at the upper portion of the same by a bolt extending through a slot in the movable plate or rib, and at the bottom by means of pin and bolt extending from the movable plate or rib through curved slots in the stationary stock, and also by a bolt extending from the upper face of the movable rib through a curved slot in a small connecting-plate, which plate is pear-shaped and is hinged at its smaller end to the stock. This connecting-plate also serves as a rib to form the bottom of the vessel, and both it and the movable plate or rib are covered by shoes of wood or other suitable material, so as not to cut the clay. Connected with the upper end of the movable rib is a lever, which, when pulled down, causes the lower end of the movable rib to move so that the edge of the same shall extend beyond the side of the stock. On the under surface of the stock is a locking device attached to a suitable lever, by which the lower end of the rib is held in this position, while the upper edge of the rib is gradually extended or moved out by means of a lever hinged to the rib and fulcrumed in and bearing against a ring on the stock. The stock is attached to the end of a sliding bar, which fits in a groove in a casting, which casting is secured to a standard. At the other end of the sliding bar is attached a rope which passes over a pulley and has a weight secured to its outer end, so as to balance the former.

I will now describe my invention so that others skilled in the art may manufacture and use the same.

In the drawings, a represents the casting, which is fastened to a suitable post or standard by screws or bolts. Down the middle of this casting extends a groove, which has inclined or beveled sides, and in this groove fits the sliding bar c , which may be secured by means of the bar b , which fits between the sliding bar

c and the edge of the groove, and the set-screw *c'*, which bears against the bar *b*.

On the sliding bar *c*, above the casting *a*, is a movable collar, *d*, which is secured by a set-screw, *d'*. The purpose of this collar is to adjust the distance which the former should be lowered.

At the upper end of the bar *c* is a ring-bolt, *d''*, to which is attached a rope, which passes thence over a pulley, and at the other end of the rope is a weight, so as to balance the former.

On the sliding bar *c* is a needle or pointer, and on the casting is a graduated scale, so as to determine the exact distance for lowering the former.

Attached to the lower portion of the sliding bar *c* is the stock *e*, on top of which rests the rib *e'*.

Extending from the upper end of the rib *e'* is a short rod or bar, *e''*, one end of which is hinged, by means of a bolt or screw, to the rib *e'*, and the other end is hinged in a like manner to the rod *e'*, which passes along the rod *c*, and is held in place by the collar *e'*.

Attached to the rod *e'* is a handle, *e''*, for moving the same, and from this handle extends a spring, *e'*, the other end of which is attached to the rod *c*.

Near the top of the rib *e'* is a longitudinal slot or opening, *f*, from the upper end of which extends, at nearly a right angle to the same, another slot or opening, *f'*.

Extending through the slot *f* from the stock *e*, is a bolt or screw, *f''*, the head of which secures a washer or ring, so that it extends over the sides of the slot, and while securing the rib *e'* to the stock *e*, allows the screw *f''* to move in the slot *f*. The edge of one side of the rib *e'*, at the upper portion thereof, is provided with a recess, *g*, above which is a projection, *g'*, the purpose of which is to form the rim around the top of the vessel.

In the lower end of the rib *e'*, on the upper surface, and at one side of the middle of the same, is a screw, *h*, which passes through a curved slot, *h'*, in the small plate or rib, *h''*, which is pear-shaped, and the smaller end of which is hinged to the end of the stock *e*.

From a point near the top of and at one side of the rib *e'* extends a rod or lever, *i*, which passes through a ring or staple, *j*, secured to the stock *e*. Through the stock *e*, near the bottom of the same, extending at an angle across the middle of the stock, is a slot, *k*, at the lower end of which is an offset, *k'*. Extending through the slot *k* is a screw or bolt, *k''*, which is secured in the rear face of the sliding former plate or rib *e'*.

Just below the slot *k* in the stock *e*, extending from the middle of the stock to the side of the same, is another slot, *k'*, through which passes a pin, *k''*, from the rear face of the rib *e'*. Below the slot *k'* in the stock *e* is a pin, *l*.

Hinged by a bolt, *l'*, to one side at the lower portion of the stock *e*, is a plate, *l''*, on the lower side of which is a notch or recess, *l'''*, and at the end of the plate is another recess, *l''''*.

Hinged to and extending from the plate *l''* to a point near the top of the stock *e* is a rod, *l'''*, the other end of which is hinged to the end of the lever *l''*, which lever is pivoted or hinged to the face of the stock *e* by a bolt, *l''''*. At the end of the lever *l''* is a handle.

On the face of the plate *l''* is a pin, *l''''*, which, by striking against the rod *l'''*, prevents the plate from being drawn too far back.

Fastened to the face of the stock *e*, near the top of the same, is a spring, *m*, which extends to the bottom of the stock. The lower end of the spring is curved so as to form a hook, *m'*.

The faces of the ribs *e'* and *h''* are covered by shoes *p* and *p'*, of wood or other suitable material, so as not to cut the clay. The under surfaces of these shoes are recessed, so as not to interfere with the screws *f''* and *h* and lever *i* when the ribs *e'* and *h''* are moved.

The operation of my improved former is as follows: The clay is placed in the mold on the wheel, the collar *d* is adjusted, and the sliding bar is lowered until the former enters the mold.

The lever *e''* is pulled forward, which pushes down the rib *e'*, it being guided in its movement by the bolt *f''* in the slot *f*, the bolt *h* in the slot *h'*, the bolt *k''* in the slot *k*, and the pin *k''* in the slot *k'*, so that when the movement is

finished the lower end of the rib *e'* shall be extended out beyond the edge of the stock *e*, while the rib *h''* is turned round, so that its side shall form a forming-edge between the ends of the stock *e* and rib *e'*, and thereby

form the bottom of the vessel. The end of the lever *l''* is then drawn back, which pushes forward the plate *l''*, so that the notch *l''''* shall engage with the pin *l* and the notch *l''* shall engage with the pin *k''*, and thereby lock the lower portion of the disks in this position.

This is necessary, as the curve *m'* of the spring *m*, having caught on the pin, has a tendency to throw the ribs back into their original position, which tendency is increased by the action of

the spring *e''*, attached to the lever *e''*. The lever *i* is then moved out from the sliding rod *c*, which moves out the upper portion of the rib *e'*, the bolt *f''* guiding the motion by the slot *f'*, and the bolt *k''* moving into the slot or offset *k'*.

This moves the edge of rib *e'* out sufficiently to form the entire inside surface of the vessel. The lever *i* is pushed back again. The lever *e''* is then pulled down, which releases the ribs *e'* and *h*, and allows them to be carried to

their original position by the force of the springs *m* and *e''*, the spring *m* acting specially to carry the bolt *k''* out of the offset *k'*. The former is then withdrawn from the mold and another vessel is formed in the same manner.

Instead of two ribs a greater number may be used, working upon the same principle, according to the shape of the vessel to be manufactured.

Having thus described my invention, what I claim, and desire to secure by Letters Patent, is—

1. In an expandible tool for forming pottery or like plastic material, the combination of a

fixed or stationary stock and a sliding forming plate or rib mounted thereon, the parts being connected by pins and cam-slots, whereby the forming-plate may be progressively projected 5 beyond the fixed stock, substantially as and for the purpose specified.

2. An expandible potter's tool consisting of a stationary stock, a movable forming-rib mounted on said stock by headed pins extending 10 and moving in slots at each end, the lower slots curving outward and downward, and the upper one being of angular shape, and levers for moving the rib so that it shall be projected first at the lower and then at the upper end, 15 substantially as and for the purposes described.

3. An expandible potter's tool having a stock, a movable forming-tool mounted on said stock, and a plate constituting the bottom former, pivoted to one part and movably attached to 20 the other by a slot and headed pin, substantially as and for the purpose described.

4. In an expandible tool for forming pottery and like plastic material, the combination of

a fixed or stationary stock, a forming-plate adapted to slide thereon, said parts connected 25 by pins and cam-slots, and a locking-plate to lock one end of the forming-plate, substantially as and for the purpose specified.

5. In an expandible tool for forming pottery and like plastic material, the combination, with 30 a fixed or stationary stock, of a sliding forming-plate mounted thereon, said parts connected by pins and cam-slots which permit a downward and outward movement of the forming-plate on the stock, a locking-plate adapted 35 to secure one end of the sliding forming-plate, and a set of springs adapted to cause the return movement of the forming-plate when the same is released by the locking-plate, substantially as and for the purpose specified. 40

In testimony whereof I have hereunto set my hand.

MAXIMILIAN WALZ.
